UNITED STATES PATENT OFFICE.

FRANK TRAVAGLINI, OF PHILADELPHIA, PENNSYLVANIA.

PAINTBRUSH HOLDER OR HANDLE.

Application filed April 6, 1927. Serial No. 181,503.

The present invention relates to an improved paint brush holder or handle, and the purpose thereof is to provide a receptacle for the reception of the drippings of paint from the brush, especially when painting overhead.

Another purpose is to provide a detachable handle or brush holder, with means, by which different brushes may be attached.

10 For instance when one brush is worn out or hardened with paint, the bristles being too stiff and incapable of being limbered, such a brush may be detached and a new brush fastened in place.

15 Another purpose is to provide, in a handle or brush holder an inside ferrule or sleeve, so positioned in the handle and so constructed, so that in case the brush is turned downwardly, the paint will be retained in the handle and prevented from dripping out and flowing back upon the brush, there being a telescoping cap or cover at the extremity of the handle, which may be removed for the removal of the collected 25 paint.

It is to be understood that the particulars herein given are in no way limitative, and that while still keeping within the scope of the invention, any desired modification of 30 details and proportions may be made in the construction of the appliance according to circumstances.

The invention comprises further features and combination of parts to be hereinafter 35 set forth, shown in the drawings and claimed.

In the drawings:

Figure 1— is a view of the improved handle or brush holder, partly in elevation 40 and partly in section, to show the interior construction thereof.

Figure 2— is a sectional view on line 2—2 of Figure 1.

Figure 3— is a cross-sectional view on line 45 3—3 of Figure 2.

Figure 4— is a detail view showing a modified form, in which a transverse bottom 3^a is shown.

Referring to the drawings, 1 identifies a 50 handle, which may be any suitable shape, preferably tapered as shown, and one end of the handle merges into a brush head receiving socket, which is provided with a bottom 3. Extending from the bottom 3^a are opposed spring blades 4, arranged in pairs. The handle, the head receiving sock-

et 2 and its bottom, as well as the spring blades 4 may be constructed of any suitable material, preferably sheet metal, which may be made up in the shape as shown by any 60 approved method. Adjacent where the bottom 3^a in Figure 4 forms an integral part with the wall of the socket, the bottom is provided with openings 5, which will permit paint that may drip into the socket, to 65 flow into the hollow handle.

6 is a paint brush, consisting of a head 7 and the brush bristles 8, the latter being fastened in the head in any approved way. The opposite side faces of the head 7 have opposing grooves 9, which receive the blades or arms 4, such arms acting to hold the brush head securely and rigidly in position. The opposite edges of the spring blades or arms have arcuately bulged portions 10, which 70 engage in corresponding shaped recesses formed in the edges of the grooves or seats 9. By this construction the head is assisted materially in being held in place and rigidity assured. To further insure holding the 75 brush head in position and to afford rigidity screws 11 pass through certain of the blades 4 and through the head 7 with their shanks threaded into sleeves 12, which are inserted through the opposite blades or arms and partly into the head 7 of the brush, as shown clearly in Figure 2, thereby providing a relatively fixed relation between the handle and 80 the brush.

It will be noted that the socket 2 is relatively larger than the head 7 of the brush, so that when the brush is being used overhead, the brush turned up and the handle down, the drippings of paint, especially when the latter is relatively thin, will flow into the 85 socket and thence into the hollow handle.

However, to prevent such paint from flowing from the handle when the brush is turned down and the handle up a sleeve or ferrule 13 is positioned within the hollow 90 handle and is held frictionally in the position shown in Figure 2. It will be noted that one end 14 of the sleeve or ferrule is so tapered as to cause the positioning of the end 15 of the sleeve from the wall of the hollow 95 handle. Obviously it may be understood by observing the drawing in connection with this description how the ferrule prevents the paint in the handle from flowing back toward the brush should it be turned down.

The extremity 16 of the handle is closed by a cap or cover 17, which is also hollow,

one end thereof being open as illustrated, the other end being closed and being of a frustoconical shape. The open end of the cap or cover telescopically fits the hollow handle, 5 and the annular shoulder 18 of the cover or cap engages with the marginal edge of the open end of the handle, thereby limiting the cap or cover in its movement toward closing the handle.

10 The invention having been set forth, what is claimed is:

1. A paint brush comprising a hollow handle having a socket on one end, a brush head of smaller size than and mounted in 15 the socket, the opposite sides of the head having parallel grooves, and means rising from the bottom of the socket and secured

in said grooves to hold the head within and spaced from the walls of the socket.

2. A paint brush comprising a hollow 20 handle having a socket on one end, a brush head provided upon opposite sides with parallel grooves, said head being relatively smaller than and being arranged in the socket, a plurality of arms upstanding from the bottom of the socket and engaged within the grooves to hold the head spaced from the bottom and the side walls of the socket, and means to retain the arms within the 25 grooves and prevent relative movement of the head.

In testimony whereof he affixes signature hereto.

FRANK TRAVAGLINI.
